BUMPER

Bartholdi Henken, Chicago, Ill.

Application April 5, 1937, Serial No. 135,122

3 Claims. (Cl. 45—137)

My invention relates to beds and includes among its objects and advantages the provision of an improved bumper.

While the bumper may be applied to beds in general, it is particularly adapted to hospital beds. In hospitals the beds are frequently grouped in large numbers in a single room, and the beds are moved from place to place, which frequently bumps one bed against another, thereby marring the finish on the bed. Such beds are usually of metallic construction provided with an enamel finish, and after a period of use the finish becomes marred. An object of my invention is to provide a bumper designed to be easily attached to beds of conventional design and in which the bumper is so located as to protect the finish on the bed incident to moving the bed against other beds.

Another object is to provide a bumper designed to embrace two bed members arranged in right-angled relation in such a manner as to effectively restrain the bumper from relative displacement with respect to the members.

A further object is to provide a bumper shaped to facilitate its attachment to the bed members and in which novel means is employed for keying the bumper in connected relation with the bed.

In the accompanying drawing:

Fig. 1 is a perspective view of a portion of a bed illustrating my invention applied thereto;

Fig. 2 is a sectional view along the line 2—2 of Fig. 1;

Fig. 3 is a sectional view along the line 3—3 of Fig. 2;

Fig. 4 is a sectional view along the line 4—4 of Fig. 2; and

Fig. 5 is a fragmentary view taken from the position indicated by line 5—5 of Fig. 4.

In the embodiment selected to illustrate my invention I make use of a bed 10 including the usual legs 12 and horizontal member 14 interconnecting the legs. While only one end of the bed 10 is illustrated, both legs 12 at the head and foot of the bed are provided with bumpers 16. These bumpers are located at the connection between the horizontal member 14 and the legs 12.

Specifically, the bumper 16 comprises a sleeve 18 of resilient material such as rubber, which sleeve has an opening 20 of such diameter as to fit snugly about the leg 12. The sleeve includes an opening 22 in its wall, which opening has its axis arranged at right angles to the axis of the opening 20 and is of such diameter as to fit snugly about the horizontal member 14. The sleeve is severed vertically at 24, which line of

severance is located centrally of the opening 22. Because of the slotted wall of the sleeve, the bumper may be connected with the bed by merely opening up the sleeve and pressing it over the leg 12 and aligning the sleeve to position the horizontal member 14 within the opening 22.

In Fig. 4, I illustrate the sleeve 18 as being provided with two openings 26 located on opposite sides of the line of severance 24 and in parallel relation therewith. A groove 28 is formed in the upper end of the sleeve for housing the bight 30 of a U-shaped fastening clip 32 having its legs 34 positioned within the openings 26. Transverse openings 36 are provided in the lower ends of the legs 34 for the reception of cotter pins 38. I recess the sleeve 18 at 40 to facilitate insertion of the pins 38 with the ends of the legs 34 terminating short of the bottom end of the sleeve. Because of the recesses 40, the pins 38 are housed within the contour of the sleeve and are not visible with the bumper attached to the bed. The clip 32 has its legs 34 so spaced as to hold the slotted ends of the sleeve 18 in slight pressure relation.

According to my invention, the bumper is effectively restrained from relative shifting longitudinally of the leg 12 because of its embracing relation with the horizontal member 14. The wall of the sleeve is sufficiently thick to constitute an effective bumper, and the location of the bumper opposite the ends of the horizontal member 14 transmits forces to the member, thus protecting the legs against bending. The bumpers protect the finish on the bed. The sleeve 18 is sufficiently thick to perform a bumping action with respect to the horizontal member 14 of an adjacent bed in addition to protecting the finish on the legs 12. In a large institution employing many beds, the beds are standardized so that the bumpers will be accurately positioned when attached to the bed according to Fig. 1. Mere connection of the bumper with the bed determines its proper location. In Fig. 4, it will be noted that the openings 26 are so positioned as to leave a small amount of material between the openings and the opening 22. In this way, I prevent contact between the clip 32 and the horizontal member 14 so as not to impair its finish should the bed be used without the bumper.

Without further elaboration, the foregoing will so fully explain my invention that others may, by applying current knowledge, readily adapt the same for use under various conditions of service.

I claim:

1. A bumper for furniture including two structural members arranged in angular relation, a bumper comprising a split sleeve having an inside diameter for the reception of one of said members, said sleeve having a bore in its wall for the reception of the other of said members, the slot in the sleeve intersecting said bore, and means associated with the sleeve to prevent separation thereof at its slot, said means comprising a U-shaped clip imbedded in the sleeve with the legs of the clip positioned on opposite sides of said last mentioned member.
2. A bumper for furniture including two structural members arranged in angular relation, a bumper comprising a split sleeve having an inside diameter for the reception of one of said members, said sleeve having a bore in its wall for the reception of the other of said members, the slot in the sleeve intersecting said bore, means associated with the sleeve to prevent separation thereof at its slot, said means comprising a U-shaped clip imbedded in the sleeve with the legs of the clip positioned on opposite sides of said

last mentioned member, and means connected with the U-shaped clip and cooperating with the sleeve to prevent removal of the clip.

3. A bumper for furniture including two structural members arranged in right-angular relation, said bumper comprising a sleeve having an inside diameter snugly fitting one of said structural members, said sleeve being provided with a bore in its wall having its axis arranged at right angles to the inside diameter of the sleeve for snugly receiving the other of said structural members, said sleeve being provided with two longitudinal openings spaced on opposite sides of its slot, a clip inserted in said openings to prevent separation of the slotted sleeve, one end of said sleeve being provided with a groove communicating with said two openings, said clip being U-shaped and having its bight housed within said groove, the lower end of said sleeve being provided with recesses communicating with said two openings, and means connected with the clip within said recesses and cooperating with the sleeve to prevent removal of the clip.

BARTHOLDI HENKEN.
